APPARATUS FOR MELTING COATING MATERIALS AND THE LIKE

Robert C. Gould, San Marino, Calif., assignor, by mesne assignments, to Brogdex Company, Pomona, Calif., a corporation.

Application July 17, 1947, Serial No. 761,727

2 Claims. (Cl. 257—198).

1

This invention relates to improvements in apparatus for melting coating materials and the like; and it relates more particularly to improvements in equipment employed in melting and maintaining in the molten state a supply of waxy material to be used in protectively coating articles such as fresh fruits and vegetables.

In the preparation of fruit and vegetables for market, it is common practice to coat them with a protective film of waxy or similar protective material in order to maintain the fruit or vegetable in good marketable condition. Certain widely employed methods of applying such a film coating involve the use of apparatus for melting the waxy material (e.g.) and then spraying or atomizing the hot molten material in order to subdivide it finely. Typical examples of wax coating apparatus in common use for this purpose are described in detail in such patents as Skinner 1,830,297, Pierce 1,940,269 and Burwick et al. 2,364,946. Such apparatus consists generally of a supply tank in which the wax is melted down and maintained in hot, highly fluid condition, and an adjacent chamber into which the liquid wax is sprayed as the articles to be coated are passed therethrough and are subjected to the action of revolving brushes. A fine spray or fog of molten wax is projected into the aforesaid chamber by a force-feed pump operating in conjunction with a compressed air supply for spraying or atomizing the liquid wax fed by the pump. For melting the wax and maintaining the molten wax sufficiently hot to be highly fluid, there is provided at a location within the tank and relatively close to the bottom thereof a heating unit in the form of a generally flat coil extending substantially parallel to the tank bottom and consisting of a plurality of turns or bends of metal tubing to which steam under suitable pressure may be supplied, or which may enclose an electrical resistance heating element arranged to be suitably connected to current supply mains. As a result of thus forming and positioning the heating unit, which makes for uniform and otherwise generally advantageous heating effect, the heating unit as a whole is, under normal operating conditions, always more or less deeply submerged in the body of hot molten wax contained in the supply tank.

Materials of the general class which apparatus of the type here involved is intended to handle melt at temperatures relatively low as compared with the melting points of the common metals, so that the heating conditions are not especially severe. Also, the manner of using the molten material does not ordinarily render it necessary

or desirable that a supply of material in molten condition be kept available in more than relatively small quantity (e.g. on the order of 5 to 10 gallons) at any given time. For most purposes, therefore, it is common and more or less established practice to employ, in apparatus of this type, a comparatively small melting tank of relatively light and inexpensive construction, made from sheet metal, for example, with welded seams or joints. Moreover, particularly because of the various piping and other connections between the tank interior and external elements of the complete spraying apparatus it has been found inconvenient and impracticable to heat-insulate the tank, whose walls are therefore exposed to the cooling effect of the surrounding atmosphere.

In practice, the apparatus may occasionally be idle for varying lengths of time; quite generally it is shut down for overnight periods. When the shutdown is to be for a substantial period, operation of the heating coil is discontinued whereupon the body of molten coating material then remaining in the supply tank gradually cools, finally cooling to below its melting point and congealing if the shutdown period is sufficiently long. In the case of a waxy coating material consisting of a mixture of a paraffin and carnauba waxes, for example, a particularly advantageous type of coating composition widely used by citrus fruit packers, especially, such melting point may be on the order of from 170° to 175° F. In solidifying from the liquid state, a body of waxy material of this type shrinks considerably in volume, often as much as 20% or even more; and when the solidified material is re-melted, a correspondingly great increase in volume occurs. If, as may often happen, there is a considerable depth of molten wax in the supply tank when the shutdown occurs, and if the duration of the shutdown and the atmospheric temperatures such as to cause congealing of the whole body of wax before operations are resumed, the heating unit is left embedded in solid coating material. Or, if the shutdown is of shorter duration and the prevailing atmospheric temperature is higher, it may be that only the upper part of the body of wax will completely solidify to form a thick hard crust. In either case, however, that portion of the supply tank containing the heating unit and occupied by the wax, whether the wax is solidified throughout the whole or only a part of its depth, sometimes becomes completely isolated and sealed off from the upper portion by an overlying thick layer of hard, solid material extending continuously between the tank walls, even though the upper

surface of this layer may be very irregular and distorted as a result of shrinkage strains undergone by the material in congealing. When the heating coil is again placed in operation preparatory to resuming normal operation of the wax-spraying apparatus, that part of the mass of solidified waxy material which is directly in contact with the coil or closest thereto is, of course, the first to be melted. Since, in melting, this part suddenly undergoes considerable expansion, and since there is no space in the sealed-off lower portion of the tank freely permitting such expansion, there must occur either rupture of the congealed body of material acting as a seal or, alternatively, rupture of the tank, in order to relieve the pressure. In actual practice, where the mass of congealed material is more than moderately thick, it is rupture of the tank (generally by splitting at the joints) which is ordinarily the more likely to occur, and it does occur at least often enough to constitute a source of substantial trouble and expense, not only because of the damage to the tank but, what may be more important, because of the time lost in forced shutdown by the plant employing the spraying apparatus. In other words, at least the major portion of the solidified mass may soften too slowly under the action of the heating coil to permit the developed pressure below said mass to force a vent opening through it for release of the melted material to the upper or exposed surface. Moreover, even if the mass or crust of congealed material does give way, it may sometimes do so almost explosively, with more or less disastrous results.

A primary object of the present invention, therefore, is to overcome the above-mentioned difficulties by provision of means for ensuring that, concurrently with the initial heating and melting of congealed waxy material immediately adjacent the heating coil, there shall be formed a pressure relief passage or vent through the superincumbent main sealing body or crust of congealed material, whereby material liquefied by the heating coil in the initial or preliminary heating operation may flow to the upper side of said body or crust, thus preventing development of excessive pressure therebelow. Further and more specific objects of the invention are to provide means of the general character stated which shall be relatively simple and inexpensive, yet dependably effective for the purpose intended; and which, in addition, is of such construction and arrangement as to require little or no structural change or arrangement of other parts commonly associated with the heating coil in wax spraying or atomizing units as heretofore commonly constructed, as well as to afford maximum convenience in assembling and disassembling the component parts of such units.

In accordance with the principles of the invention, its general objective is achieved by the provision of heating means comprising a tubular heater of suitable metal which encloses the steam or other source of heat employed, located wholly or in the lower part of the tank and hence, when the apparatus is operating, submerged in its entirety in the body of molten material in direct contact therewith; together with a metallic member, constituting a blow-hole former, which is in good heat-transmitting contact with the wall of said tubular heater, by integral metallic union or otherwise, whereby to ensure rapid transmission of heat units from the latter to said member. Such blow-hole forming member extends upwardly within the tank to a level not substantially

below that of the upper surface of any congealed body of coating material likely to be formed in the tank even if, at the time of shutdown, the tank is filled to maximum capacity with molten coating material.

The objects, novel features and advantages of the invention will become further apparent from the following description, taken in conjunction with the accompanying drawings which illustrate one desirable practical form of apparatus embodying the invention, it being understood that this specific embodiment is intended as illustrative only and not restrictive.

In the drawings,

Fig. 1 is a view in side elevation of the coating material supply tank, partly in section on the line 1—1 of Fig. 2;

Fig. 2 is a plan view of the apparatus with the tank cover removed; and

Fig. 3 is an enlarged cross-section of a detail taken on the line 3—3 of Fig. 2, looking in the direction of the arrows.

Referring to the drawings, the wax supply tank, indicated generally at 10, has side walls 11, bottom 12 and a removable cover 13. Mounted within the tank near its bottom is the tubular heater, here shown as consisting of a flat heating coil 14, which in this case is of the steam type and is generally serpentine in shape, having all its turns or loops lying in a plane substantially parallel to but spaced slightly above the bottom of the tank and from the side walls thereof. This coil is provided at opposite ends with unions 15 and 16 by which it is connected to steam supply and return lines 15a and 16a, respectively, for easy removal from the tank for repairs or replacement. As shown, said lines extend directly through the tank wall at about the level of the coil for connection therewith. At a point on the upper surface of heating coil 14, this point being indicated generally in the drawings at 17, an internally threaded metal socket member 18, here shown as an ordinary nut, is secured in firm metallic union to the coil, as by welding indicated at 18a. This socket member receives and securely holds the threaded end of a metal riser 19, in this instance a solid rod, which is screwed solidly thereto and thus supported vertically within the tank. Said riser, which is here shown as of sufficient length to project somewhat above the maximum level of melted wax, indicated at 20, normally maintained in the tank, should possess heat-transmitting capacity ample to transmit heat from the coil 14 to congealed wax in contact with the riser, rapidly enough to melt that wax simultaneously with the melting effected by said coil. A riser composed of steel will serve the purpose, or if a metal having greater heat conductivity is used, such as brass, the same heat-transmitting effect may be obtained with a riser of smaller diameter. With this arrangement, when heat is supplied to the heating coils in re-starting the equipment for operation after a shutdown, not only the wax immediately in contact with the coil is melted, but also that in contact with vertical riser 19 which receives and transmits heat by conduction from the coil on which it is mounted. In this manner, a small annular outlet or "blow-hole" is created around the riser in the body of congealed wax, so that the wax initially melted by the heating coil in the lower part of the tank can escape upwardly through the overlying mass of congealed wax. This prevents development of any substantial pressure due to expansion of melting wax below the solid mass.

Removably mounting the heat-transmitting riser on the heating coil 14, especially when this is accomplished through use of the specific mounting means here shown and described, affords important practical advantages. Removability of the riser is desirable because other pieces of equipment included in the wax melting and spraying unit are customarily associated with the heating coil in the supply tank; and, due to the limited working space available in the tank, assembling the various component parts housed therein, or disassembling them as may sometimes be necessary, is much more easily accomplished if the riser is detachable from the coil. Utilizing as the mounting base a nut solidly welded to the tubing of the coil is a convenient, inexpensive and particularly satisfactory way to hold the riser securely in good metallic (heat-transmitting) engagement with the steam or electrically heated coil. In the present example, the other pieces of equipment contained in the tank as just mentioned include a force-feed device 21, a compressed air reservoir 22, an air header 23, all connected to spraying or atomizing air jets outside the tank, as well as the heat-sensitive element 25 of a thermo-control device (not shown) for regulating the amount of steam supplied to the heating coil 14. These parts are indicated in dotted lines only, and more or less diagrammatically, since they constitute no part of the present invention.

It will be readily apparent that various other forms of heat-conductive risers, in rod or other form, can be employed to obtain the same or a sufficiently similar result. For example, it is possible to form coil 14 with a loop rising vertically to the proper height from the plane of the rest of the coil. However, especially where thin-walled steel tubing is used as is desirable, fabrication of a coil in such special form is somewhat difficult and relatively expensive. Again, coil 14 could be provided with a vertically extending branch in the form of a tubular stub closed at its upper end and teed at its lower end into the coil itself to permit steam to flow into the tube directly. It is also possible to weld a vertical riser directly to the coil itself. Apparatus em-

bodying these, as well as many other detailed changes and modifications, while still utilizing the essentials of the invention and realizing the benefits thereof in at least substantial degree, is to be understood as included within the scope of the invention as defined by the appended claims.

What is claimed is:

1. An apparatus for melting waxy materials which expand upon passing from solid to liquid state which comprises, in combination with a tank: a substantially flat heating coil within said tank adjacent the bottom thereof and virtually parallel thereto, an upwardly directed, threaded member secured to the coil, and a heat-conductive, blow-hole forming extension rod removably connected to the threaded member and extending upwardly to project substantially through a mass of waxy material congealed from the maximum volume of molten waxy material which the tank is arranged to contain.
2. In an apparatus, including a tank, for melting materials which expand upon passing from solid to liquid state, the provision of: a heating coil provided with a removable, blow-hole forming member, said heating coil being substantially flat and arranged to be positioned adjacent the bottom of a tank; an internally threaded member secured to the upper side of the heating coil by a fused metal connection; and a rod-like, heat-conductive, blow-hole forming member removably screwed into the internally threaded member, said blow-hole forming member extending upwardly to project substantially through a mass of material congealed within said tank.
